UNITED STATES PATENT OFFICE.

REES DAVIS, OF CHICAGO, ILLINOIS.

DESIGN FOR A DOLL.

60.446.

Specification for Design. Patented Feb. 21, 1922.

Application filed February 18, 1921. Serial No. 446,176. Term of patent 3½ years.

To all whom it may concern:

Be it known that I, REES DAVIS, a citizen of the United States, residing at Chicago, in the county of Cook and State of Illinois, have invented a new, original, and ornamental Design for a Doll, of which the following is a specification, reference being had to the accompanying drawing, forming a part thereof.

The drawing is a perspective view of a doll, showing my new design.

I claim:

The ornamental design for a doll as shown.

REES DAVIS.
